(57) **CLAIM**

The ornamental design for a bottle cap, as shown and described.

DESCRIPTION

FIG. 1 is a perspective view of a bottle cap in an open position;

FIG. 2 is a left side view thereof, with the right side view being a mirror image thereof;

FIG. 3 is a rear elevation view thereof;

FIG. 4 is a front elevation view thereof;

FIG. 5 is a top plan view thereof; and,

FIG. 6 is a bottom plan view thereof.

The broken lines depict environment, and portions of the bottle cap, and form no part of the claimed design. The dot-dash broken line(s) defines the bounds of the claimed design and form no part thereof.
